UNITED STATES PATENT OFFICE.

HUGH KENNEDY, OF SHARPSBURG, PENNSYLVANIA.

HOT-BLAST STOVE.

SPECIFICATION forming part of Letters Patent No. 398,970, dated March 5, 1889.

Application filed August 15, 1887. Serial No. 246,933. (No model.)

To all whom it may concern:

Be it known that I, HUGH KENNEDY, of Sharpsburg, in the county of Allegheny and State of Pennsylvania, have invented a new 5 and useful Improvement in Hot-Blast Stoves; and I do hereby declare the following to be a full, clear, and exact description thereof.

My invention relates to fire-brick hot-blast stoves; and its object is to cheapen and simplify 10 their construction, to reduce the expense of maintenance, and to save manual labor in their operation.

The efforts of constructors and improvers of hot-blast stoves have been largely directed 15 to economy in gas, the theory being that all the heat possible should be extracted from the gas before it escaped to the stack-flue. This has led to the devising and construction of stoves so expensive to erect and maintain 20 that the advantage arising from their economy in gas is nearly, if not quite, overbalanced thereby. My practical experience in blast-furnace practice has been that most of the modern blast-furnaces produce more gas 25 than is necessary for heating the blast, and that the excess is allowed to go to waste. It is therefore unnecessary that the stoves of such furnaces should be constructed with special reference to economy of gas, and the consequence 30 is that cheaper stoves, if capable of heating the air properly, will do just as well as those at present used.

The object of my invention is the production of a cheap and effective blast-heating apparatus.

To enable others skilled in the art to make and use my invention, I will now describe it by reference to the accompanying drawings, in which—

40 Figure 1 is a vertical longitudinal section of a plant of four stoves embodying my invention on the line A A of Fig. 2. Fig. 2 is a horizontal section on the line B B of Fig. 1. Fig. 3 is a vertical cross-section on the line C C of Fig. 2, showing the stoves “on gas.” Fig. 4 is a similar section showing the stoves “on air.”

Like figures of reference indicate like parts wherever they occur.

50 The stoves, of which a plant of four is shown in Figs. 1 and 2, are constructed of fire-brick and have the usual external sheet-iron casing, 5. They may be empty chambers, as at 1, or

have vertical walls projecting from their inner surface, or be provided with checker-work 55 or hollow bricks. In the latter two instances the filling should be supported by suitable arches in the usual way to an open chamber at the bottom. These instances of variation are mere statements as to how the heating-surface in the interior of the stove may be increased, if desired, and not given with a view of claiming such construction or of limiting my invention to the use of any particular construction or arrangement of the heating-surfaces, as any good and adequate construction of the same will do. The air-inlet 8 is placed at one end of the row of stoves, and the hot-air outlet 9 at the other end. There is a separate gas-inlet, 10, at or near the base of each 70 stove and a separate gas-outlet, 11, at the top of each stove. The stoves communicate with each other by openings through the partition-walls.

It is necessary that there should be at least 75 two stoves, although as many more as may be desired may be connected therewith, and the air-exit of each should be at the opposite end from the air-inlet. Thus in Fig. 1 the air-inlet 8 of the stove 1 is at the base and the air-outlet is the opening 12, by which the stove 1 communicates with the stove 2, and in like manner the outlet of the stove 2 is at the bottom, being the opening 13, by which it communicates with the stove 3, and the outlet 85 of the stove 3 is at the top, being the opening 14, by which it communicates with the stove 4. The air entering at the inlet 8 passes alternately up and down, and after traversing the entire length of each stove passes out at 90 the outlet 9, which, it will be understood, is connected with the hot-air flue leading to the furnace. The inlet 8 is provided with a valve, 15, and the outlet 9 with a valve, 16, so that they can be closed when the stoves are put 95 on gas. The gas enters each stove at the gas-inlet 10 near the bottom and passes directly up through the stove and out through the gas-outlet 11 at the top of the same. The gas is supplied through the usual gas-flue, 33, 100 Figs. 3 and 4, whence it passes into the stove by means of a pipe, 17, leading from the flue 33 up to the gas-inlet opening 10. This pipe 17 may, if desired, be fixed; but I prefer the construction shown, in which the upper part, 105 18, of this pipe is movable, being secured to

a slide, 19, which rests on a bed-plate, 20, and is reciprocated by means of a rack, 21, and pinion 22. By this construction the horizontal end of the pipe 18 can be moved forward 5 into the gas-inlet 10 or drawn backward out of it. When it is moved forward, its lower end registers with the upper end of the stationary part of the pipe 17 and communication is established between the gas-flue 33 and the 10 stove, as shown in Fig. 3, and when the slide 19 is drawn back the pipe 18 is retracted from the gas-inlet and the solid part of the slide covers the upper opening of the pipe 17, thereby acting as a valve to close the same. 15 The gas-inlet 10 is then closed by a door, 23, as shown in Fig. 4, which when the inlet is opened is either removed or suspended above the inlet, as shown in Fig. 3. Air for the combustion of the gas is admitted by an annular 20 opening formed around the gas-pipe 18 by making such pipe of smaller diameter than that of the gas-inlet 10, as shown in Figs. 1, 2, and 3. The gas-outlet 11 is controlled by a sliding door or valve, 24, which moves laterally 25 across the top of the outlet in guides or ways 25, being operated by a shaft, 26, by means of a pinion, 27, mounted on the shaft engaging with a rack, 28, attached to the slide 24. (See Figs. 2, 3, and 4.) The shaft 26 extends along 30 the top side of the stoves, and by means of the construction named operates all of the top valves of the group of stoves. It is provided at one end or any other convenient place with a pulley, 29, from which a suitable chain or 35 belt, 30, extends to the pulley 31, mounted on a shaft and operated by a windlass, 32, near the ground, or by other suitable power appliance.

When it is desired to take the stove off 40 gas, the connection-pipes 18 are withdrawn, the gas-inlets 10 closed, and then the sliding valves 24 at the tops of the stoves are closed. If it is desirable to protect the bed-plate and guides 25 of the valve 24 from the heat of 45 the escaping gases, it can be done by the use of a short pipe or tube, 34, Figs. 1, 3, and 4, which is pivotally connected to the outer end of the guide-plate 25 by rods 35, one on each side, which in turn are pivotally connected 50 to the pipe at a suitable point above the guide-plate, and by pivotally connecting the pipe by means of longer rods, 36, one on each side, to the valve 24, the said rods 36 being also pivotally connected to the valve. When 55 thus connected the pipe 34 occupies a vertical position over the gas-outlet 11 when the valve 24 is open, the lower end of the pipe extending down inside of the guide-plate 25 and resting upon the top of the stove; but 60 when the valve 24 is closed the rods 36 push it up out of its seat and cause it to turn on the rods 35, so that it is not only raised out of its seat, but moved backward and deposited on the top of the stove out of the 65 way of the valve, thereby permitting the latter to come to its seat over the gas-outlet 11, as illustrated in Fig. 4. The pipe 34 thus

acts as a chimney to the stove. I do not, however, limit myself to the slide-valve 24, as it is evident that I can close the gas-outlet 11 by other well-known means—such, for instance, as the ordinary damper. This is a detail of construction which may be modified in various ways by the skilled furnace-builder.

These stoves must each have a direct passage for the gas from the gas-inlet to the gas-outlet, while the air traverses the entire series, entering at or near one end of one stove and passing thence to the next stove 80 at or near the other end, and so on, traversing every stove of the series, whether there be two, three, or more, before it passes out at the exit.

I do not herein claim the within-described 85 construction of detachable connections between the gas-flue 33 and the stoves, nor indeed any other feature of construction not specifically set forth in the following claims.

What I claim as my invention, and desire 90 to secure by Letters Patent, is—

1. The combination of a series of hot-blast stoves, connected by alternate high and low openings, forming a continuous air-passage therethrough, with separate gas-inlets at the 95 base and separate gas-outlets at the top of each stove, substantially as and for the purposes described.

2. The combination, in a hot-blast stove, of a gas-outlet at the top, with a sliding valve 100 for closing the same, and a pipe pivotally connected by rods to the sliding valve, and also pivotally connected by rods to a stationary point on the opposite side from the valve, so that when the valve is opened the pipe 105 shall occupy a vertical position over the gas-outlet, and when the valve is being advanced to close the outlet the pipe shall be raised out of the path of the valve, substantially as and for the purposes described.

3. The combination, with a row or series of hot-blast stoves, each having a gas-outlet at the top controlled by a sliding valve provided with a rack, of a power-shaft extending transversely to the valves and provided 115 with pinions engaging the racks, a pulley on said shaft, and a chain or belt extending to near the ground for actuating the shaft, substantially as and for the purposes described.

4. A series of hot-blast stoves having air-ports opening from one to the other, each stove of the series being provided with a gas inlet and outlet port, so that the gas shall pass through each stove independently of the 125 other, and the air shall pass from one stove to the other, substantially as and for the purpose specified.

In testimony whereof I have hereunto set my hand this 6th day of August, A. D. 1887.

HUGH KENNEDY.
